COMB

Arthur Rogovin, 245 Rumsey Road,
Yonkers, N.Y. 10701

Filed June 17, 1970, Ser. No. 23,524

Term of patent 14 years

Int. Cl. D28—03

U.S. Cl. D86—8

FIG. 4

FIG. 2

FIG. 1

FIG. 3

FIG. 1 is an elevational view of a comb showing my new design, the side opposite being reversely similar;

FIG. 2 is a side edge view of the same;

FIG. 3 is a view of the opposed side edge of the same; and

FIG. 4 is a top plan view of the same.

I claim:

The ornamental design for a comb, substantially as shown and described.
